RHEOSTAT HOUSING

Carl Weissenstein, New York, N. Y., assignor to
Carol Electrical Control, Inc., Brooklyn, N. Y.,
a corporation of New York

Application November 12, 1952, Serial No. 22,225

Term of patent 14 years

(Cl. D26—5)

To all whom it may concern:

Be it known that I, Carl Weissenstein, a citizen of Czechoslovakia and a resident of the city of New York, in the county of Queens and State of New York, have invented a new, original, and ornamental Design for a Rheostat Housing, of which the following is a specification, reference being had to the accompanying drawing forming a part thereof.

Fig. 1 is a top view of a rheostat housing, showing my design.

Fig. 2 is a side view thereof, the opposite side being the same.

Fig. 3 is a front view thereof, and

Fig. 4 is a rear view thereof.

I claim:

The ornamental design for a rheostat housing, substantially as shown and described.

CARL WEISSENSTEIN.
